LENS ASSEMBLY FOR INDUSTRIAL SAFETY HELMETS

John F. Clark, Wyomissing, Pa., assignor to
Willson Products, Inc., Reading, Pa., a corpora-
tion of Pennsylvania

Application December 10, 1941, Serial No. 422,344

2 Claims. (Cl. 128—143)

My invention relates to industrial protection helmets and particularly to those employed in sand blasting operations requiring a sight opening, and more specifically it relates to new and useful improvements in the lens assembly for such sight opening; my objects being to simplify the construction, avoid the damage of sand grinding between movable parts, and cushion the assembly against jarring shocks and danger of breaking the lens.

The nature of my improvements and their manifest advantages will be more fully understood in connection with the following specification and the drawing accompanying the same, setting forth a detailed description of a full embodiment of my invention, the novel features of which are pointed out in the appended claims.

Fig. 1 is a front elevation of a protective helmet embodying my improved lens assembly for the sight apertures.

Fig. 2 is a corresponding side view of the same.

Fig. 3 is an enlarged scale partial vertical section on the line 3—3 of Fig. 1, showing my improved lens assembly mounted on the sight aperture of the helmet.

Fig. 4 is a front view of the showing in Fig. 3 the cap and screen being partly broken away to show the underlying parts.

Fig. 5 is a reduced scale exploded view of the parts shown assembled in Fig. 3, the upper halves being shown in vertical section corresponding to the sections shown in Fig. 3.

Referring to the drawing, 1 indicates a helmet, preferably made in known manner of rubber deposited on a wire frame so as to provide a desirably flexible cover for self adjustment and to absorb sound and shock of flying abrasions. This helmet has a sight opening formed by a circular flange portion 2 surrounding an aperture in the helmet in line with the eyes of a wearer, such flange being an integral rigid part of the helmet and having spaced bolting flanges 3 to secure a lens assembly according to my present invention. An air line tube for supplying fresh air to the interior of the helmet is indicated at 4, but the body harness, dust-proof seal, and other features of the helmet not essential to the present disclosure, are omitted from the drawing.

My improved lens assembly consists of a ring 5, preferably of light weight metal, having bolting flanges 6 registering with the flanges 3 and secured to the latter by screw bolts 7. The inner face of this ring 5 is recessed at 8 to form a seat for a lens 9, preferably of laminated glass, and also preferably having a protective cover lens 10

of cellulose acetate to prevent pitting of the lens. A second recess 11 is provided to receive a lens retaining spring ring 12, which is formed of bent spring wire with spaced ends so it may be sprung into and out of its retaining seat recess 11. The annular end of the ring 5 forms a bearing seat 15 for the flat rim portion 16 of an outwardly domed perforated screen member 17, the perforations being so numerous as to permit sight there-through, and small enough to protect against large flying fragments from impinging against the lens. On the outer surface of the ring 5, adjacent the bolting flanges 6, a rib 20 is formed, having an inclined surface 21 leading to a locking shoulder 22.

The lenses 9 and 10 and their retaining ring 12 are introduced and removed through the outer end of the ring 5, and to prevent their accidental displacement, and to secure the rim 16 of screen 17 seated on its bearing seat 15, I provide a retaining cap 30. This cap 30 is made of yielding material, preferably of rubber, so that it may be snapped over the ring 5 and act also as a shock absorbing cover for the latter to soften the jars 25 and shocks of flying fragments. The cap 30 is formed with an inwardly directed flange 31 at one end overlying the annular ring seat 15, and when engaged, securely holds the screen rim 16 in firmly seated position. At the other end of the 30 cap it is interiorly recessed at 32 so as to cooperatively engage under the shoulder 22 of ring 5. No tools are required to remove and replace this cap and there can be no grinding friction of any sand or grit that may be lodged between it and its ring 5.

My improved lens assembly thus fully described insures firm holding in position of its several parts, provides for absorbing shocks and jars against the ring 5, and may be simply and cheaply made with a minimum of expensive machining, or screw threading liable to be severely damaged by the grinding action of interposed sand.

In practice I have found the above specific construction preferable as set forth, but the construction described may of course be modified within the spirit of my invention as defined in the following claims.

What I claim is:

1. In a helmet having a sight opening, a lens assembly therefor comprising a rigid frame member secured to said sight opening and having an annular edge seat, recessed internal seats for a lens and a lens-retaining spring, and an external annular locking rib encircling said frame adjacent said sight opening, a lens protecting screen

seated on said annular edge seat, and a retaining ring of flexible material having an inwardly directed flange at one edge adapted to overlie said annular end seat and a locking recess adjacent its other edge adapted to engage with said annular locking rib.

2. In an industrial protection helmet having a sight opening provided with an encircling lens-holding frame having an annular outer edge seat,

an exterior locking rib extending around said frame, and a lens-protecting screen seated on said edge seat, a shock-absorbing cap of flexible material for said frame having a flange portion adapted to hold said screen to its edge seat and a ring portion with an interior recess adapted to exteriorly engage said frame and lockingly engage said frame locking rib.

JOHN F. CLARK.
